(57) **CLAIM**

The ornamental design for a digital camera, as shown and described.

DESCRIPTION

FIG. 1 is a top, side and rear perspective view of a digital camera showing my new design;

FIG. 2 is a front elevational view thereof;

FIG. 3 is a rear elevational view thereof;

FIG. 4 is a top plan view thereof;

FIG. 5 is a side elevational view thereof from the right of FIG. 2; and,

FIG. 6 is a top, front and side perspective view thereof.

The structure in dotted lines is shown only to indicate the environment of the present invention and its appearance is not claimed.
